SMOKER'S PIPE

Jesse T. White, Holmes, N. Y.

Application August 10, 1939, Serial No. 289,347

4 Claims. (Cl. 131—198)

This invention relates to smokers' pipes and is herein illustrated as embodied in a briar pipe having a usual type of removable mouth piece.

One of the objectives in satisfactory smoking for many smokers is the obtaining of a cool smoke, but the ideal sought for has never been reached. Another sought for object is an easily cleaned pipe, but these two objects have hitherto proved incompatible in practice partly because of the fragile or complicated construction hitherto deemed essential in order to get the needed parts into the restricted limits of a standard smoker's pipe.

According to the present invention as herein illustrated an easily removable tube is provided around which circulates cooling air, while an internal core separates the hollow of the tube into passages in which smoke passes back and forth with the result that the foregoing difficulties and objections are overcome, and a smoker's pipe is provided which is rugged in structure, simple in design, cheap to build, easily dismounted to clean and effective in cooling.

Other features and advantages will hereinafter appear.

In the accompanying drawing—

Figure 1 is a longitudinal section through a pipe embodying one form of the invention.

Figure 2 is a transverse section on the line 2—2 of Figure 1.

Figure 3 is a side view of the internal tube.

Figure 4 is a side view of the core.

Figure 5 is a bottom view of the same.

Figure 6 shows a hook for ready removal of the tube.

In the form shown the mouthpiece 10 of the pipe is rabbeted at 11 so that it slips into the usual bore 12 of the pipe-stem 13 which terminates at the side opening 14 at the bottom of the bowl 15.

In the form shown the bore 12 is uniform throughout the stem 13 and contains an aluminum tube 16 having an end annular boss 17 which abuts against the end 18 of the mouth-piece 10 and a second end annular boss 19 which centers the tube 16 in the side opening 14 at the bottom of the bowl 15.

When the pipe is thus smoked the smoke draws in smoke through the tube 16, and causes some of the tobacco in the bowl 15 to be burned by air entering a bottom opening 20 in the mouth-piece end of the stem 13 and flowing in the annular passage 21 between the tube 16 and the inner surface of the bore 12 of the stem 13. The annular boss 19 is shown flat at 22 permitting the

free flow of air from the annular passage 21 into the bowl 15. Thus air entering the passage 21 cools the smoke within the tube 16, and, in the form disclosed does this efficiently, because the tube 16 illustrated is made of aluminum and may be as thin as paper since no strain comes upon it.

Usually the pipe also includes a core 23 which is shown in the form of an aluminum rod fitting closely within the tube 16 but easily slideable therein. The core is shown as ground out to form three channels or passages 24, 25, 26, through which the smoke is drawn as follows:

The smoke enters the bottom channel 25 through an opening 27 drilled in the solid end 28 of the core, said opening delivering the smoke only into the channel 25, and the smoke flows toward the mouthpiece in the channel, which is closed by the tube wall 16. The channel 25 terminates about a half inch from the butt end 18, and one side is cut away there at 29 so the smoke flows through the cut 29 into the channel 24. In the channel 24 the smoke flows toward the bowl until it reaches the base of the annular boss 19, where it flows through a cut 30 into the channel 26 which carries it out the end of the tube 16, into the mouthpiece 10. The entrance of the channel 26 into the mouthpiece 10 is shown as a centrally drilled opening 31 in the end of the core, thus enabling the circular wall of the core to

serve as a firm mounting for the core in the mouthpiece 10, seating itself against a rabbet face 32. In the form shown the core is easily removed from the mouthpiece 10 as for cleaning.

Just outside the mouthpiece an opening 33 is drilled through the bottom of the channel 26, into a pocket 34 hollowed out of the core and separated from the cut 29 by a solid wall 35 left in the metal. This pocket 34 forms a temporary receptacle for any moisture condensing or flowing into the channel 26.

The core described is made of aluminum thus forming a continuation of the metal tube or sleeve as an excellent heat conductor to abstract heat from the smoke, and forming a closed channel for each channel 24, 25, 26.

To enable the tube 16 to be readily removed, it is shown as provided with an opening 36 adapted to be caught by the turned up end 37 of a hook 38 which conveniently fits the smoker's finger at 39. Since the opening 36 is within the annular boss 17 and is closed by the wall of the stem 13, the opening may be safely a perforation as shown.

Having thus described one embodiment of the invention, what is claimed is:

1. A smoker's pipe having a bowl in which to

bacco burns, a hollow stem ending in a mouth-piece, a tube within the hollow stem to form an annular channel around said tube, an annular boss supporting the tube at the mouthpiece, a second annular boss at the bowl adapted to let air pass from the annular channel in the stem into the bowl, and a core removably slideable in the tube and providing a channel for leading smoke out of the bowl towards the mouthpiece, a second channel leading back to near the bowl, and a third channel leading to the mouthpiece.

2. A smoker's pipe having a bowl in which tobacco burns, a hollow stem ending in a mouth-piece, a tube within the hollow stem to form an annular channel around said tube, an annular boss supporting the tube at the mouthpiece, a second annular boss at the bowl adapted to let air pass from the annular channel in the stem into the bowl, and an aluminum core removably slideable in the tube and providing a channel for leading smoke out of the bowl towards the mouthpiece, a second channel leading back to near the bowl, and a third channel to the mouth-piece.

3. A smoker's pipe having a bowl in which tobacco burns, a hollow stem ending in a mouth-

piece, a tube within the hollow stem to form an annular channel around said tube, an annular boss supporting the tube at the mouthpiece, a second annular boss at the bowl adapted to let air pass from the annular channel in the stem into the bowl, and a core removably slideable in the tube and removably mounted on the mouth-piece and providing a channel for leading smoke out of the bowl towards the mouthpiece, a second channel leading back to near the bowl, and a third channel to the mouthpiece.

4. A smoker's pipe having a bowl in which tobacco burns, a hollow stem ending in a mouth-piece, a tube within the hollow stem to form an annular channel around said stem, an annular boss supporting the tube at the mouthpiece and including an opening for removing it, a second annular boss at the bowl adapted to let air pass from the annular channel in the stem into the bowl, and a core removably slideable in the tube and providing a channel for leading smoke out of the bowl towards the mouthpiece, a second channel leading back to near the bowl, and a third channel to the mouthpiece.
